UNITED STATES PATENT OFFICE

HANS SATTLER, OF MUNICH, GERMANY

GUIDE DEVICE FOR NECKTIES

Application filed October 16, 1928, Serial No. 312,799, and in Germany July 14, 1928.

- At the putting on of neckties, immaterial if long neckties or bows or stand-up collars or turned-down collars are used, exists the inconvenience that the necktie either slips 5 down and settles between collar and shirt or that, for instance on turn-down collars, the necktie which at the tying has to be pulled to and fro, sticks between the two parts of the collar and is damaged.
- 10 Clamplike devices have become known designed to prevent slipping down of the necktie. These devices are however not adapted for all kind of collars or they do not provide sufficient clearance for pulling 15 the necktie to and fro.
- This invention relates to a guiding device for neckties, adapted as well for stand-up collars as for turn-down collars and which as well prevents slipping down of the necktie 20 as permits of an easy pulling of the necktie, the latter being at the same time guided at the correct height as the guiding element is adjustable in vertical direction.
- An embodiment of the invention is illustrated, by way of example, in the accompanying drawing in which 25 Fig. 1 shows the guiding device in application.
- Fig. 2 is a rear elevation of the same.
- 30 Fig. 3 shows the guiding device in side elevation.
- Fig. 4 is also a side elevation showing the necktie guide adjusted in vertical direction.
- The guiding element according to the invention 35 consists of a clamp *a*, the front part of which forms a plate designed to prevent tipping of the guiding element at the pulling of the necktie *f*. The rear arm of the clamp *a* serves to guide an adjustable 40 loop *b*, having a sleeve *c* shiftable on this longer arm of the clamp to adjust the guide element in accordance with the height of the collar.
- The lower bent end *d* of the loop *b* serves 45 to retain the necktie and to hold the resilient arms of the loop in parallel position so that the necktie can be freely pulled.
- The clamp *a* of the guiding device is designed to be pushed from below over the 50 collar *e* whereupon the guide loop *b* is ad-
- justed in vertical direction and the necktie inserted into this loop.
- Two guide devices are preferably used, one at each side of the collar.
- The plate *a* of the necktie guide which is 55 visible on stand-up collars is preferably painted in the color of the necktie or white. The guiding device may be made of any suitable material.
- I claim:—
- 60 A guiding device for neckties, comprising in combination a clamp, a loop, and a sleeve arranged on the outside of said loop, fastening said loop vertically adjustable on said clamp.
- 65 In testimony whereof I affix my signature.
- 70 HANS SATTLER.
